UNITED STATES PATENT OFFICE.

DUNCAN C. HOOKER, OF FARMINGTON, CONNECTICUT, ASSIGNOR, BY MESNE ASSIGNMENTS, TO DIAMOND POWER SPECIALTY CORPORATION, OF DETROIT, MICHIGAN, A CORPORATION OF MICHIGAN.

PROTECTION FOR SOOT BLOWERS.

Application filed December 29, 1921. Serial No. 525,543.

This invention relates to that form of soot-blowers for water-tube steam boilers wherewith soot, ash and kindred products of fuel combustion are removed from the exterior surfaces of the boiler tubes by the agency of jets of steam directed thereon from nozzles incorporated in the blower tube that extends across the boiler tubes in a position adjacent thereto. Such blower tubes are commonly mounted in bearings attached to some of the boiler tubes so as to be axially rotatable for the purpose of varying the direction of the steam jets, and one end extends through the boiler setting and on the outside is provided with a swivelled header comprising suitable means of rotation and valves to control the admission and flow of steam to the blower pipe.

The blower tubes owing to their location within the boiler setting in the path of the gases of combustion, are subjected to the same intense heat as the boiler tubes themselves. But, unlike the boiler tubes, which are continually cooled by the presence and flow of water and the generation of steam within, the temperature of the soot-blower tubes is relieved by no such cooling agency except at infrequent intervals for periods of short duration when steam is turned through them to clean the boiler tubes. The continual subjection of the blower tubes to such intense heat renders them liable to rapid deterioration.

The object of the present invention is to provide a stationary metallic casing about the blower tube which will so protect the blower tube from the destructive action of the direct rays of heat from the fire that the tube may be made of common cheap metal, such for instance as mild steel tubing, which casing is constructed of parts assembled in such a way as to permit the easy and quick replacement of those parts of the casing which may from time to time become burned out, without disturbing the parts which are not injured, and without interfering with any parts of the blower or its fittings, and the shapes of the various parts of the casing being such that they may be made of many of the recently developed heat resisting and non-corrod़ing metals that cannot be used for the blower tube as they cannot be drawn or formed and welded into tubing, although they may be

readily cast or rolled into sheets from which 55 semi-cylindrical sections, such as are made use of in the construction illustrated, may be easily formed.

In the accompanying drawings Figure 1 shows a section of a water-tube boiler in 60 which is installed a soot-blower arranged and protected according to this invention. Fig. 2 shows on larger scale a longitudinal section of the adjoining ends of two lengths 65 of the protecting casing and their supporting and clamping means. Fig. 3 shows a transverse section of the blower tube and a protecting casing on the dotted line 3—3 on Fig. 2. Fig. 4 shows a transverse section of the parts on the dotted line 4—4 on Fig. 70 2. Fig. 5 shows a side elevation of the blower tube support which is also used for supporting the sections of the protecting casing. Fig. 6 shows an end elevation of the support. Fig. 7 shows a plan of the split clamping 75 ring which is used to hold the casing sections in place. Fig. 8 shows a side view of the clamping ring. Fig. 9 shows a top view of the tapered drift collar which is employed to hold the top of the clamp ring together. Fig. 10 shows a side view of the collar. Fig. 11 is a view looking into the top section of 80 one length of protecting case. Fig. 12 is a view looking into the bottom section of one length of the protecting case. 85

In the illustrations of the water tubes 1, steam drums 2 and boiler setting 3 are of common form and arrangement. But one soot-blower tube 4 with nozzles 5 is represented. This soot-blower tube extends transversely of the water tubes and is supported by bearing plates 6 which in the construction shown are clamped to alternate water tubes by shackle bolts 7. On the end of the soot-blower tube outside of the setting is a 90 steam admission head 8 provided with means 9 of conventional design whereby the blower tube may be rotated.

On each side of each of the soot-blower supporting plates is a hub 10. Shaped to fit 100 on these hubs and extending between the adjacent supporting plates are the semi-circular protecting plates 11 and 12, the upper plate being substantially the same as the lower plate except that it is provided with ports 13 through which the jets of steam 105 may be projected from the blower tube. When these plates are assembled on the sup-

porting hubs they form a continuous tube about and protection for the blower tube. After the ends of adjacent lengths of the plates have been located on the hubs, clamp 5 rings which comprise a member 14 and a member 15 are placed around them so as to encircle the ends and hold them in place on the hubs of the supporting plate. These clamp ring members are desirably semi-circular and on the under side one has a mortise 16 and the other a hooked tenon 17 that can be readily engaged or disengaged when the members of the clamping ring are swung open at the top but that cannot come apart 10 when the members of the clamping ring are drawn together at the top. Slidable on the supporting plates is a collar 18 that preferably has a tapering opening. At the top the clamping ring members have lugs 19 shaped 15 to fit within the collar. When the collar is dropped it fits over the lugs of the clamp ring members and holds them together. When the collar is lifted the clamp ring members may be opened out and taken off 20 leaving the sections of the protecting case which are shown as semi-cylindrical but need not be exactly semi-cylindrical, free to 25 be removed.

The invention claimed is:

- 30 1. The combination with the water tubes of a steam boiler, of a soot blower tube, a plurality of bearings, means connecting the water tubes and bearings for supporting the blower tube at intervals in spaced relation from said water tubes, said bearings adapted to permit rotation of the blower tube therein, and a stationary protecting case surrounding the blower tube and mounted on said bearings.
- 40 2. The combination with the water tubes of a steam boiler, of a soot blower tube, a plurality of bearings, means connecting the water tubes and bearings for supporting the blower tube at intervals in spaced relation from said water tubes, said bearings adapted to permit rotation of the blower tube therein, and a stationary protecting case surrounding the blower tube and mounted on said bearings, and means for clamping the case on the said bearings.
- 50 3. The combination with the water tubes of a steam boiler of a soot blower tube, means

supporting the soot blower tube from the water tubes and a case enclosing the blower tube, said case being formed in semi-cylindrical lengths with the ends of the several lengths fastened to said blower tube supporting means.

4. The combination with the water tubes of a steam boiler of a soot blower tube, means 60 supporting the soot blower tube, said means having laterally projecting hubs through which the blower tube extends, and a sectional protecting case enclosing the blower tube, the ends of the sections of said case 65 being mounted on and fastened to the hubs projecting from the blower tube supporting means.

5. The combination with the water tubes of a steam boiler of a soot blower tube, 70 means supporting the blower tube, said means having laterally projecting hubs, a casing enclosing the blower tube, said casing being formed in sections with the ends of the sections fitting said hubs, split rings 75 surrounding the ends of the sections of the case and holding them to said hubs, and means for holding the ring members together.

6. The combination with the water tubes 80 of a steam boiler of a soot blower tube, means supporting the soot blower tube, said means having laterally projecting hubs, a sectional case surrounding the blower tube with the ends of the sections fitting said 85 hubs, split rings encircling the ends of the casing sections and holding them to the hubs, said split ring members having engaging mortises and tenons at the bottom and lugs at the top, and collars slidable on the 90 supporting means and engaging said lugs and holding the tops of the ring members together.

7. The combination with a soot blower of 95 supporting plates, said plates having perforations through which the soot blower tube passes, a sectional protecting case enclosing the blower tube with the ends of the sections fastened to said blower tube supporting plates and held thereby with a space 100 between the blower tube and the inner walls of the case.
